UNITED STATES PATENT OFFICE.

SISSAK K. OUZOUN-BOGHOSIAN, OF WASHINGTON, DISTRICT OF COLUMBIA.

DESIGN FOR A TALKING-MACHINE CABINET.

57,990.

Specification for Design.

Patented May 24, 1921.

Application filed June 14, 1920. Serial No. 389,013. Term of patent 3½ years.

To all whom it may concern:

Be it known that I, SISSAK K. OUZOUN-BOGHOSIAN, a subject of the Sultan of Turkey, having declared my intentions of becoming a citizen of the United States, residing at Washington, District of Columbia, have invented a new, original, and ornamental Design for Talking-Machine Cabinets, of which the following is a specification, reference being had to the accompanying drawing, forming part hereof.

The figure is a perspective view of a talking-machine-cabinet, showing my new design, which is adapted to fit thereto two sets of phonographic-parts, which cabinet is provided with two sound-amplifiers and a set of four drawers.

I claim:—

The ornamental design for a talking-machine cabinet, as shown.

In testimony whereof I affix my signature.

SISSAK K. OUZOUN-BOGHOSIAN.
